UNITED STATES PATENT OFFICE.

JOHN FRANCIS PEREY AND HUBERT PEREY, OF BROOKLYN, NEW YORK

TURNSTILE.

1,254,065.

Specification of Letters Patent. Patented Jan. 22, 1918.

Application filed July 30, 1897. Serial No. 183,627.

To all whom it may concern:

Be it known that we, JOHN FRANCIS PEREY, a citizen of the United States of America, and HUBERT PEREY, a subject of the

5 Queen of the Netherlands, both residing at the city of New York, borough of Brooklyn, county of Kings, State of New York, have invented certain new and useful Improvements in Turnstiles, of which the following is a specification.

Our invention, while relating generally to turnstiles, has particular reference to the form and construction of turnstile arm and locking mechanism for the same.

10 One of the serious objections to turnstiles now in common use, arises as a result of injuries suffered by persons in attempting to force a passage, after paying their fare but before the locking mechanism of the machine is released. This has resulted in heavy losses to companies operating these machines and created a demand for a modified type in which either ordinary or extraordinary force or pressure exerted by a person against 15 the arm of the machine which bars the passage, will cause the arm to yield and, in yielding, will operate to effect the release of the locking mechanism of the machine, thereby obviating not only the main cause 20 of risk and danger to patrons but also making it impossible for the plaintiffs in damage suits to establish what has heretofore been considered the most important fact on which such suits are based, *i.e.*, that the machine 25 was rigid and unyielding.

Further, in many instances it is desirable to employ a turnstile merely for the purpose of automatically registering the number of persons passing and in such uses, there is 30 no occasion for having an attendant manually release the machine for each person but it is important and essential to accuracy in the count, that the movement of the turnstile be definitely limited to a quarter revolution for each person, assuming a four arm 35 machine to be employed.

With these objections and demands for improvements in mind, we have produced a machine which we believe will fully meet 40 the situation and prove both efficient and satisfactory in use.

In the accompanying drawings, forming part of these specifications, we have illustrated a construction suitable for carrying 45 our invention into effect. We wish it understood, however, that we do not limit our-

selves to either the exact form or the precise details shown, as various changes may be made therein without departing from the spirit and scope of the present invention. 60

In the drawings:

Figure 1 is a view in side elevation of our improved turnstile, the upper part only of the machine being shown;

Fig. 2 is a similar view partly in section; 65

Fig. 3 is a plan view in which, to avoid useless repetition, one arm only and a portion of the head is shown;

Fig. 4 is a cross sectional view, taken on the line *s*, *s*, of Fig. 3, and showing the 70 position of the arm when the machine is at rest;

Fig. 5 is a similar view, showing the position of the arm when operated to release and permit free rotation of the turnstile head. 75

Fig. 6 is a view in elevation with parts shown in section of a modification; and

Fig. 7 is a detail plan view of the locking bolt.

Referring now to the drawings, 1 represents the upper portion of the base casting or pedestal of the turnstile. This casting is hollow or chambered and has mounted within and centrally thereof, a vertically disposed shaft 2, the upper end of which is 85 reduced to form a shoulder at 3.

Fitted loosely on the shaft and resting on the shoulder 3, there is a separating washer 4, which supports the rotating head 5, of the machine clear of the pedestal. 90

The head 5, for convenience of removal, is loosely mounted on the upper projecting end of the shaft 2, but is keyed or connected to rotate with it through the top plate 6. 95

As shown, the top plate is snugly fitted on the squared end 7, of the shaft and is secured by lock-nuts 8. Thus mounted, the shaft and plate are connected together in fixed relation and through studs or pins 9, 100 projecting from the underside of the plate and entering sockets in the head, rotation of the head, in either direction, is transmitted to the shaft.

The head 5, may be given any form desired but is preferably square, as indicated in Fig. 3, to provide flat surfaces to receive the turnstile arm supports and the head locking devices, which will now be described. 105

The particular form and construction of the arm support is not important, it being 110

essential only, for the type of arm here disclosed, to provide two bearings at 10, 10, preferably radially alined with relation to the head 5. As shown, the support consists 5 of a straight radially disposed rod 11, which is secured to the head by having one of its ends screwed into a threaded socket 12 of the head, and the other firmly held against movement, by a brace rod 13, secured thereto 10 by a bolt 14. The inner end of the brace rod is also threaded in the head and extends outward therefrom in the horizontal plane of the straight rod 11.

The arms, as shown, are rectangular and 15 each comprises two tubular sections 15, 15, of substantially the same length as the supporting rod 11, and arranged in parallel relation as shown. These tubular sections are connected by means of end castings 16, 16, 20 into which they are threaded.

The straight rod extends through one of the tubular sections 15, and serves as a support upon which the arm is free to turn, it being limited, however, in its rotary movement about the support, as will be herein- 25 after described.

Normally or when the machine is not in operation, the arms are held in the position shown best in Fig. 4, with the upper tubular member thereof lying beyond the support and thus advanced, will naturally be grasped or pushed against by a person in going through the passage in which the machine is located and under the pressure thus 30 applied, the arm yields and is rocked forward to the position shown in Fig. 5, before there is any rotary movement of the head carrying the arms.

This preliminary independent movement 40 of the arm is utilized to effect the release of a head locking device arranged in connection with each arm and there shown in the form of a flat bolt 17, which is slidingly mounted in a recess 18, of the head and 45 limited in its movement by a headed stud or screw 19, projecting through a slot 20, in the bolt.

The locking bolt is normally shot downward by a spring 21, acting through a 50 notched lever 22. The spring is carried by the brace rod 13, on which the lever 22, is pivoted and a stud 23, projecting from the lever into an elongated opening 24, in the locking bolt completes the connection from the spring through which it acts to yieldingly maintain the bolt at the limit of its downward movement, as shown in Fig. 4.

The raising or release of the bolt in opposition to the spring, by the preliminary 60 rotary movement of the arm about its horizontal supporting axis, is effected through a connection between the arm and the lever 22. As shown, the free end of the lever is extended at 22^a, and is connected through a 65 pin 22^b, with a projecting lug 25, of the

inner end casting of the arm, the arrangement being such, that movement of the arm from the position shown in Fig. 4, to that in Fig. 5, operates to throw the free end of the lever upward against the action of the 70 spring and at the same time raises the locking bolt clear of the stop 26, on the pedestal of the machine, permitting rotation of the head through a quarter revolution in the usual manner well known in the art. 75

As before stated, each arm is provided with a head locking device similar to that above described and as the arms, one after the other, come into position barring the passage in which the machine is operating 80 the locking bolts thereof successively co-act with the stop 26, on the pedestal and check further rotation of the machine, until the bolt is released in the manner above described. 85

Ordinarily, a ratchet mechanism is employed to prevent back or reverse motion of the machine and as it is desirable to simplify the machine and reduce its cost as much as possible, we find that by forming 90 a second stop 27, on the pedestal and giving it an inclined surface 28, it will serve practically every purpose of the ratchet mechanism. The purpose of inclining the upper surface of this second stop, is to cam the 95 locking bolt upward and cause it to ride over it and immediately the bolt passes it, the spring acts and shoots the bolt downward between the two stops, preventing further rotation of the machine in either direction. 100

In Figs. 6 and 7, we have shown a modification in which only one locking bolt or mechanism is employed to coöperate with the several arms of the rotating head. 105

As shown in Fig. 6, the locking bolt 17^a is contained in a casing 18^a, which is bolted to the upper end of the pedestal of the machine. The body of the bolt is cylindrical and is slidingly fitted in the casing under 110 the action of a spring 29, which tends to maintain it at the limit of its upward movement. The bolt is squared or flattened at its upper end, as indicated at 30, and said squared or flattened portion projects through 115 a slot 31 formed in a screw cap 32, which is threaded in the bolt casing.

Coöoperating with the locking bolt, just described, there are a series of lugs 26^a and 27^a, which are secured to the rotating head 120 of the machine, there being two of such lugs provided in connection with each arm of the turnstile.

In the modification, the arm supports and the spring advanced arms mounted therein 125 are of the same construction as previously described, and there is provided in addition a projection 32, from each arm, which extends downward between the lugs and is designed as the arm is rocked, in the manner 130

previously described, to cam the locking bolt downward and clear of the lugs, thereby disengaging the same and permitting rotation of the head, necessary for a single operation of the machine. The return of the bolt to locking position on the completion of such operation is effected by forming inclined surfaces as indicated at 26° and, thus constructed and arranged, it will be seen that under rotation of the head, the inclined surface of the lug, for example, that shown on the right in Fig. 6, will ride into engagement with the projecting end of the locking bolt and by reason of the incline, cam the locking bolt downward until the lug passes it, whereupon, under the reaction of the spring, the bolt shoots upward, coming into position between the lugs and again locking the machine preparatory to the next operation.

As shown in Fig. 6, the inclined lugs are arranged so that on disengagement of the locking bolt in the manner just described, the machine may be rotated in either direction, assuming the usual ratchet mechanism is not present. It is only in very rare instances that free rotation of the machine in either direction after being unlocked is required and in order now to change the machine over to rotation in one direction only, for example, toward the right or clockwise, it is only necessary to remove and reverse each of the right hand lugs 27°, as indicated by dotted lines in Fig. 6, in which position the lug acts as a positive stop against return or backward movement of the head, by presenting its squared end to the locking bolt. To adapt the machine for rotation toward the right or counter-clockwise only, the reversal of the right hand lug 26° of each pair would bring about the desired result, as will be apparent.

As the operation of the machine will be apparent from the foregoing description, further detailed explanation is deemed unnecessary and will therefore not be given.

Having, therefore, fully described our invention, we claim:

1. A turnstile provided with a rotatable head, a plurality of arms carried by the head and rotatable therewith, the said arms being mounted to each have limited movement independent of the head, and locking means for the head arranged to be released by the said limited independent movement of the arms.

2. A turnstile provided with a rotatable head, a plurality of arms carried by the head, each arm being mounted to have movement independent of the head, and head locking means operatively connected to be released by the independent movement of the arms.

3. A turnstile provided with a rotatable head, arm supports fixed to the head, radially disposed arms mounted in the supports to have limited movement independent of the head, and locking means for the head operatively connected to be released by the limited independent movement of the arms. 70

4. A turnstile provided with a rotatable head, arm supports fixed to the head, radially disposed arms mounted in the supports to have limited movement independent of the head, and a head locking device carried by each arm and connected to be operated by the limited independent movement of the arms. 75

5. A turnstile provided with a head, rotatable about a vertical axis, a plurality of 80 arm supports fixed to the head, outwardly extending arms mounted on the supports to have limited rotation about horizontal axes, and head locking means controlled by the movement of the arms about the horizontal 85 axes.

6. A turnstile provided with a head, rotatable about a vertical axis, a plurality of 90 arm supports fixed to the head, outwardly extending arms mounted on the supports to have limited rotation about horizontal axes, springs opposing such limited rotation, and head locking means controlled by the movement of the arms about the horizontal axes. 95

7. A turnstile provided with a head, 95 rotatable about a vertical axis, a plurality of arm supports fixed to the head, outwardly extending arms mounted on the supports to have rotation about horizontal axes, springs and stops limiting such rotation; and head 100 locking means controlled by the movement of the arms about the horizontal axes.

8. A turnstile provided with a head rotatable about a vertical axis, a plurality of 105 arm supports fixed to the head, outwardly extending arms mounted on the supports to have rotary motion about horizontal axes, springs opposing such rotary motion in one direction and stops limiting it in the opposite direction, and a locking bolt for the 110 head carried by each arm and controlled by its movement about horizontal axis.

9. A turnstile provided with a head rotatable about a vertical axis, a plurality of 115 arm supports fixed to the head, a head locking bolt carried by each support, and outwardly extending arms movably mounted in the supports to control the bolts.

In testimony whereof, we affix our signatures, in the presence of two witnesses.

JOHN FRANCIS PEREY.
HUBERT PEREY.
